US00D610764S

(12) **United States Design Patent**
Massip et al.

(10) **Patent No.:** US D610,764 S
(45) **Date of Patent:** ** Feb. 23, 2010

(54) **LAUNDRY IRON**

(75) Inventors: **Victor Massip**, Nantes (FR); **Laurent Lebot**, Nantes (FR)

(73) Assignee: **Rowenta Werke GmbH**, Offenback am Main (DE)

(**) Term: **14 Years**

(21) Appl. No.: **29/329,470**

(22) Filed: **Dec. 16, 2008**

(30) **Foreign Application Priority Data**

Jul. 14, 2008 (EM) 000969860-0001

(51) **LOC (9) Cl.** **07-05**

(52) **U.S. Cl.** **D32/70**

(58) **Field of Classification Search** D32/68-73;
38/69, 74-75, 77.1-77.9, 79, 88, 90, 93;
219/245-252, 259

See application file for complete search history.

(57) **CLAIM**

The ornamental design for laundry iron, as shown and described.

DESCRIPTION

FIG. 1 is a front, left, top perspective view of the laundry iron, showing our design;

FIG. 2 is a left view thereof;

FIG. 3 is a right view thereof;

FIG. 4 is a front view thereof;

FIG. 5 is a rear view thereof;

FIG. 6 is a top view thereof; and,

FIG. 7 is a bottom view thereof.

The broken lines shown in the drawings are included for the purpose of illustrating environmental structure and form no part of the claimed design.
